UNITED STATES PATENT OFFICE.

HERBERT WHEATLEY RIDSDALE, OF LONDON, AND STANLEY SMITH COOK, OF WALLSEND, ENGLAND, ASSIGNEES TO CHARLES ALGERNON PARSONS, OF NEWCASTLE-UPON-TYNE, ENGLAND.

COMBINED AHEAD AND ASTERN TURBINE.

1,022,215.

Specification of Letters Patent.

Patented Apr. 2, 1912.

Application filed July 28, 1911. Serial No. 641,050.

To all whom it may concern:

Be it known that we, HERBERT WHEATLEY RIDSDALE, a subject of the King of Great Britain and Ireland, and residing at Capel 5 House, 62 New Broad street, London, England, and STANLEY SMITH COOK, a subject of the King of Great Britain and Ireland, and residing at Turbinia Works, Wallsend-on-Tyne, in the county of Northumberland, 10 10 England, have invented certain new and useful Improvements in and Relating to Combined Ahead and Astern Turbines, of which the following is a specification.

This invention relates to improvements in 15 combined ahead and astern turbines of the type described in the Serial No. 608,583, February 14, 1911, in which a single dummy or balancing piston is adapted to enable the required balancing thrust to be obtained when 20 either the ahead or the astern turbine is in action, such balancing piston being arranged at the admission point to one turbine and connected to the admission space of the other turbine through the interior of a hollow 25 rotor or by suitable external pipe means.

Considerable economy in steam consumption is obtained, as is already well known, by admitting low pressure steam exhausted from auxiliary engines to a low pressure 30 stage of a turbine. In combined ahead and astern turbines, however, such exhaust steam is usually admitted to a low pressure stage of the ahead turbine and it has been necessary to provide special pipe connections 35 and valves therein by which the supply of auxiliary steam can be bypassed when the astern turbine is in action.

The object of the present invention is to 40 overcome such a disadvantage and to provide an arrangement of turbines according to the above patent in which the existing pipe means can be used for the admission of such exhaust steam.

The invention consists for this purpose in 45 a combined ahead and astern turbine of the above type in which a branch connection from the external pipe means controlled by a three-way valve is adapted to place one side of the single balancing or dummy piston in communication with a lower pressure 50 stage of either the astern or the ahead turbine, low pressure steam from the auxiliary engine being admitted to said external pipe means at a point therein between the three-

way valve and dummy piston whereby said steam is supplied to either the ahead or astern turbine.

The invention also consists in the improved combined ahead and astern turbine hereinafter described.

In the form of turbine illustrating by way of example one method of carrying the present invention into effect, the ahead turbine comprises an impulse wheel, *a*, followed by reaction sections, *b*, and *c*, preferably separated by a stepped part, *d*, on the combined turbine rotor, while the astern turbine has an impulse wheel, *e*, followed by a reaction section, *f*. Steam is admitted to the turbines from a supply pipe, *g*, by a three-way valve, *h*, to pipes, *i* and *j*, leading respectively to the inlet nozzles of the ahead and of the astern turbine, both of which turbines exhaust into a common eduction pipe, *k*. At the ahead turbine end of the rotor, 75 there is a single dummy or balancing piston, *l*, placed in front of the impulse wheel, *a*, and separated from the chamber containing the latter, by a packing, *m*, placed between the piston and the turbine casing. The side 80 of the piston, *l*, remote from the astern turbine is placed in communication with a low pressure stage of the astern turbine, for example with the chamber containing the impulse wheel, *e*, by means of external pipe 85 connections, *n* and *o*, while communication between the dummy piston, *l*, and a lower pressure stage of the ahead turbine is established through a pipe connection, *p*, branching from the pipe connection, *n*, and leading to the chamber containing the annular surface, *d*, between the two portions, *b* and *c*, of the ahead reaction part. The adjustment necessary for establishing communication between the space behind the dummy 95 piston, *l*, and the stage of the astern turbine or of the ahead turbine, is effected by means of a three-way valve, *q*, adapted to control the passage of steam from the pipe connection, *n*, to the connection, *o* or *p*, respectively, the adjustment of this valve being preferably effected simultaneously with the opening of the valve, *h*, by which steam is admitted to either turbine part. For this purpose the valve *h*, as shown, is of the 100 ordinary slide valve type and has a sliding part, *r*, mounted upon a rod, *s*, which can be moved by rotating a hand wheel, *t*, which

has a screw threaded connection therewith. The movement of the sliding piece, *r*, effects the uncovering of one of the ports *u* or *v*, whereby steam is admitted either into 5 the pipe connection, *i* or *j*. The three-way valve *q*, is also of the ordinary slide valve type, having a sliding piece, *w*, mounted upon a rod, *x*, connected to the valve rod, *s*, by a pivoted member, *y*, so that on the valve 10 part *r* being moved, in one direction, the valve part, *w*, moves in the opposite direction to uncover one of the ports, *z*, or *l*, by which steam is admitted from the pipe, *n*, to the pipe, *p*, or to the pipe, *o*, respectively. 15 When the ahead turbine is in action, the valves are arranged as shown in the figure, from which it will be seen that steam from the supply pipe, *g*, will pass through the valve port, *u*, into the pipe connection, *i*, 20 leading to the ahead turbine inlet nozzles, while the piston, *l*, will be subjected to the pressure of the steam in a lower stage of the ahead turbine on account of this stage being now in communication through the pipe 25 connection, *n*, port, *z* and pipe connection, *p*.

Obviously when the slide valve, *r*, is moved to the left and the slide valve, *w*, to the right, steam will be admitted from the supply pipe, *g*, through the port, *v*, to 30 the pipe, *j*, and astern turbine, while at the same time the dummy piston, *l*, will be put in communication with a lower pressure stage of the astern turbine by means of the pipe connections, *n* and *o*, which are now in 35 communication through the open port, *l*.

According to the present invention, exhaust steam from an auxiliary engine is admitted to either turbine part by utilizing the already existing pipe connections, this 40 being effected by leading such steam into the system by means of a branch pipe connection, *2*, preferably from the pipe, *n*. Such an arrangement insures that it will be unnecessary in all cases to provide special 45 means for regulating such exhaust steam, as in consequence of the adjustment of the three-way valve, *q*, being effected simultaneously with that of the main valve, *h*, such steam will always be admitted to an active 50 turbine stage. Further, any steam leaking past the packing, *m*, will be conducted back to and used in the reaction section, *c*, of the ahead turbine, in which the low pressure 55 steam admitted by the pipe connections, *2*, and *p*, from the auxiliary engines, is further utilized.

During the operation of the astern turbine, any steam leaking through the packing, *m*, passes through the reaction blading, 60 *b*, and *c*. On account of the very slight drop of pressure, the quantity of leakage steam however is so small in proportion to the available cross sectional areas of the ahead turbine, that the leakage steam can 65 not have any harmful influence.

Instead of the dummy piston being placed at the ahead turbine end, it can equally well be arranged at the astern turbine end, the pipe connections in such a case being correspondingly reversed. The arrangement 70 shown in the accompanying drawings, however, is much more suitable since the difference of pressure across the packing gland where the shaft passes through the turbine casing, is less than when the dummy is 75 placed at the astern turbine end of the rotor.

Though turbines having impulse sections followed by reaction sections have been illustrated, it will be seen that turbines having 80 reaction sections only may be used in the turbine according to the present invention, and that many other modifications may be made in the details of construction without in any way departing from the spirit of 85 the invention.

Having now described our invention what we claim as new and desire to secure by Letters Patent is:—

1. In a turbine having ahead and astern 90 turbine parts, a single balancing piston, connecting means by which one side of said piston is subjected to the pressure in a stage of either turbine part when in action, and means for supplying said stage with 95 additional working fluid which passes thereto through the existing connecting means.

2. In a turbine having ahead and astern turbine parts, a single balancing piston, external pipe means placing one side of the 100 piston in communication with a stage of the turbine part in action, and means for supplying said stage with additional working fluid which passes thereto through the existing pipe means.

3. In a turbine having ahead and astern turbine parts, a single balancing piston, external pipe means adapted to place automatically one side of said piston in communication with a stage of the turbine part in 110 action, and means for supplying said stage with additional working fluid which passes thereto through the existing pipe means.

4. In a turbine having ahead and astern turbine parts, a single balancing piston, external pipe means capable of placing a stage of either turbine part in communication with one side of the balancing piston, valve controlling means situated in the pipe means and adapted to place said piston in communication with the turbine part in action, and means whereby a stage of the active turbine part is supplied with additional working fluid which passes thereto through the existing pipe means.

5. In a turbine having ahead and astern turbine parts, a single balancing piston, external pipe means adapted to place a stage of either turbine part in communication with one side of the balancing piston, valve 130

- controlling means situated in the pipe means and adapted to place the piston in communication with the turbine part in action, and means placed between said valve means and the piston, whereby additional working fluid can be passed through the existing pipe means and supplied to the turbine part in action.
6. In a turbine having ahead and astern turbine parts, a single balancing piston, an external pipe connection placing one side of the balancing piston in communication with a stage of one turbine part, a branch pipe connection from said external pipe connection to a stage of the other turbine part, a three-way valve between said pipe connection and the branch pipe therefrom, and means admitting additional working fluid to said pipe connection between the valve and piston whereby said fluid is admitted to either turbine part and the turbine is balanced during either ahead or astern movement.
7. In a turbine having ahead and astern turbine parts, a single balancing piston, an external pipe connection placing one side of the balancing piston in communication with a stage of one turbine part, a branch pipe connection from said external pipe connection to a stage of the other turbine part, a three-way valve between said pipe connection and the branch pipe therefrom, and means admitting additional working fluid to said pipe connection between the valve and piston, and means adjusting the three-way valve simultaneously with the admission of fluid to one of the turbine parts in order to subject the piston to the pressure of the fluid in the active turbine part whereby said additional working fluid is admitted to either turbine part and the turbine is balanced during either ahead or astern movement.
8. In a turbine having ahead and astern turbine parts comprising one or more impulse stages followed by a reaction section, a balancing piston placed at the inlet end of the ahead turbine part, an external pipe connection placing one side of the piston in communication with an impulse stage of the astern turbine, a branch pipe connection leading from the external pipe connection to a stage of the ahead turbine reaction section, a three-way valve placed at the junction of the branch pipe connection with the external pipe connection, positively actuated means adjusting the three-way valve to subject the balancing piston to the pressure of the fluid in a stage of the active turbine part thereby balancing the propeller thrust due to the latter, and means admitting additional working fluid to the external pipe connection between the valve and the piston whereby the additional working fluid is supplied to either turbine part by means of the existing pipe connections.

connection between the valve and the piston whereby this fluid is supplied to either turbine part by means of the existing pipe connections.

9. In a turbine having ahead and astern turbine parts comprising one or more impulse stages followed by a reaction section, a balancing piston placed at the inlet end of the ahead turbine part, an external pipe connection placing one side of the piston in communication with an impulse stage of the astern turbine, a branch pipe connection leading from the external pipe connection to a stage of the ahead turbine reaction section, a three-way valve placed at the junction of the branch pipe connection with the external pipe connection, means acting upon said valve simultaneously with the admission of fluid to one of the turbine parts to place the piston in communication with the turbine part in operation, thus allowing said piston to be subjected to the fluid pressure in either turbine part, and means admitting additional working fluid to the external pipe connection between the valve and the piston whereby this fluid is supplied to either turbine part by means of the existing pipe connections.

10. In a turbine having ahead and astern turbine parts comprising one or more impulse stages followed by a reaction section, a balancing piston placed at the inlet end of the ahead turbine part, an external pipe connection placing one side of the piston in communication with an impulse stage of the astern turbine, a branch pipe connection leading from the external pipe connection to a stage of the ahead turbine reaction section, a three-way valve placed at the junction of the branch pipe connection with the external pipe connection, positively actuated means adjusting the three-way valve to subject the balancing piston to the pressure of the fluid in a stage of the active turbine part thereby balancing the propeller thrust due to the latter, and means admitting additional working fluid to the external pipe connection between the valve and the piston whereby the additional working fluid is supplied to either turbine part by means of the existing pipe connections.

In testimony whereof, we affix our signatures in presence of two witnesses.
